LESLIE H. COLBURN, OF FRANKLIN, PENNSYLVANIA, ASSIGNOR TO COLBURN
MACHINE TOOL COMPANY, OF FRANKLIN, PENNSYLVANIA, A CORPORATION
OF PENNSYLVANIA.

COMPOUND TABLE FOR DRILL-PRESSES.

1,068,324.

Specification of Letters Patent.

Patented July 22, 1913.

Application filed January 29, 1912. Serial No. 673,980.

To all whom it may concern:

Be it known that I, LESLIE H. COLBURN, citizen of the United States, residing at Franklin, in the county of Venango and 5 State of Pennsylvania, have invented certain new and useful Improvements in Compound Tables for Drill-Presses, of which the following is a specification.

The object, construction, operation and 10 advantages of my invention are herein set forth with sufficient clearness to enable those skilled in the art to which it appertains, to make and use the same.

The object of my invention is to provide 15 a compound table for drill presses, and more especially an adjusting means for same, whereby the two movements of the table—which are relatively transverse to each other,—may be independently but simultaneously 20 accomplished by the operator from one position at the front of the table.

A compound table for a drill-press is not 25 novel, neither is the matter of the adjustability of such table in two directions, but so far as I am aware, no adjusting means has been provided whereby the operator may, from one position, and simultaneously but independently, adjust such table in the two directions,—that is laterally, also forward or backward, and it is such a construction that I have invented and seek to secure 30 by Letters Patent. I am aware however, that in certain types of machine tools employing compound tables, the adjusting mechanisms for the various movements of 35 the table have been connected by gearing, so that the actuation of said adjusting mechanisms is simultaneously accomplished by means of one crank or hand wheel, but such 40 adjustment lacks the independent feature which characterizes my construction.

The construction whereby I attain said object is clearly set forth in the drawings, the various figures of which are as follows:—

Figure 1 is a plan view of a compound table embodying my invention; Fig. 2 is a front elevation of same; Fig. 3 is a side elevation thereof; Fig. 4 is a plan view of the 50 saddle; Fig. 5 is a front view of the saddle; Fig. 6 is one of the pinions used for adjusting the saddle and table. Fig. 7 is a side elevation of a drill-press equipped with my improved compound table.

The construction here shown is substantially as follows:—Upon any suitable support, as 1, which is located beneath the spindle of the drill-press, is mounted a saddle 2 arranged in any suitable way, to have a forward and backward movement or adjustment upon said support 1. Upon said saddle is mounted a table 3, arranged in any suitable way, to have a lateral movement or adjustment, which movement is in a fixed line transverse to the movement of saddle 2. 60 In proximity to each outer corner of said saddle, is formed a pocket 4, 5, for the reception of a spiral pinion 6, 7,—see Fig. 6. Upon the upper face of support 1, and positioned beneath pinion 6, is rigidly attached 70 a rack 8, with which pinion 6 meshes. Upon the lower face of table 3, and positioned above pinion 7, is rigidly secured a rack 9, with which pinion 7 meshes. The longitudinal dimensions of said racks extend in 75 a fixed line at a right angle to each other. Pinions 6 and 7 are each rigidly attached to a shaft 10, for the reception of which, suitable bearings 11 and 12 are formed integrally with the saddle 2. Said bearings 80 11 and 12 extend obliquely outward from the outer corners of said saddle, and the outer end of each shaft 10 is suitably formed for the reception of a manipulating means, such as capstan wheels 13 and 14. From an 85 inspection of Figs. 1 and 2, it will be noted that said wheels 13 and 14 are positioned in close proximity to each other and are within easy reach of the operator, so that one wheel may be operated with one hand, and the other wheel with the other hand, simultaneously but independently. It will also be further noted especially by an additional 90 inspection of Figs. 4 and 5, that said adjusting wheels 13 and 14 always maintain 95 their relative position, regardless of the adjustments made: whereas, with all other devices of this class the adjusting devices move with their respective elements, and their relative position changes accordingly.

When it is desired to adjust the saddle 2, wheel 13 is turned, which causes pinion 6 to revolve and to travel upon rack 8, either outwardly or inwardly, as desired, and this causes a corresponding movement of said 100 saddle and the superimposed table 3. When it is desired to adjust the table 3 laterally, wheel 14 is turned, which causes pinion 7 to

revolve and to move rack 9 and table 3, either to the right or left, as desired, and as above stated, wheels 13 and 14 may be simultaneously turned and both adjustments, as above set forth, be simultaneously accomplished: on the other hand, with all other forms of adjusting devices, except as above stated while it is possible at some positions of the adjusted elements, to reach both of the adjusting devices and adjust their respective members or elements simultaneously, at other positions thereof, it is not possible to do this, owing to the fact that said devices move with their said respective elements, and are so far apart that they can not both be reached at the same time for simultaneous manipulation. It will thus be readily understood that, by the use of my improved adjusting device, much economy of time and labor may be secured.

The pinion 6, which moves the saddle, is a left-hand spiral, and pinion 7, which moves table 3, is a right-hand spiral.

A shield 15 for the rack 8 is formed upon the apron 2, to protect said rack from the chips and borings from the drill.

As a usual thing, the knee or bracket 1 of a drill-press is vertically movable, so that work of varying thicknesses may pass beneath the drill or other tool that is secured in the lower end of the spindle 16, but so far as the application of my invention is concerned, this may or may not be the case.

I claim—

1. In a compound table for drill presses the combination of a suitable base adapted to be positioned beneath the spindle of such press, an element consisting of a saddle adjustably mounted upon said base, a second element consisting of a table adjustably mounted upon said saddle, an intermeshing pinion and rack arranged for adjusting said saddle, an additional intermeshing pinion and rack arranged for adjusting said table, both of said pinions being carried by one of said elements, whereby their relative positions remain unchanged when adjustments are made, and means for revolving said pinions.

2. In a compound table for drill-presses, the combination with a bracket attached to and vertically adjustable upon the column of a drill-press, of a horizontally-adjustable saddle mounted upon said bracket, a table mounted upon said saddle and adjustable thereon, in a line transverse to the line of adjustability of said saddle, a rack attached to the upper face of said support extending parallel to the line of adjustability of said saddle, a shaft revolvably mounted in said saddle, with its axis positioned obliquely to the line of adjustability of said saddle and its outer end extending frontwardly, a pinion keyed to the inner end of said shaft, meshing with said rack for the purpose set forth,

forth, a rack attached to the lower face of said table and extending parallel to the line of adjustability thereof, a second shaft revolvably mounted in said saddle, with its axis positioned at substantially a right angle to said first-mentioned shaft and its outer end also extending frontwardly, a pinion keyed to said last-mentioned shaft, meshing with said table-rack for the purpose set forth, and means arranged so as to be accessible to the operator from one position for revolving said shafts simultaneously or independently.

3. In a compound table for drill presses the combination of a suitable base adapted to be positioned beneath the spindle of such press, an element consisting of a horizontally-adjustable saddle mounted upon said base, a second element consisting of a horizontally-adjustable table mounted upon said saddle, an intermeshing pinion and rack arranged for adjusting said saddle, an additional intermeshing pinion and rack arranged for adjusting said table, both of said pinions being carried by one of said elements, a shaft, upon which each of said pinions is mounted for the purpose of revolving same, said shafts being provided with bearings in said pinion-carrying element, and means for revolving said shafts.

4. In a compound table for drill-presses, the combination with a bracket attached to and vertically adjustable upon the column of such press, of a horizontally-adjustable saddle mounted upon said bracket, a table mounted upon said saddle and horizontally adjustable thereon in a fixed line transverse to the line of adjustability of said saddle, a rack attached to the upper face of said support extending parallel to the line of adjustability of said saddle, a shaft revolvably mounted in said saddle with its axis positioned obliquely to the line of adjustability and its outer end extending frontwardly, a pinion rigidly affixed to the inner end of said shaft arranged to mesh with said rack for the purpose set forth, a rack attached to the lower face of said table and extending in a line parallel to the line of adjustability thereof and at a right angle to said first-mentioned rack, a second shaft revolvably mounted in said saddle and extending diagonally outwardly with its axis positioned at substantially a right angle to said first-mentioned shaft, a pinion keyed to the inner end of said last-mentioned shaft arranged to mesh with said table-rack for the purpose set forth, and means arranged to revolve said shafts simultaneously and independently.

5. In a compound table for drill presses, the combination of a suitable base positioned beneath the spindle of such press, a saddle mounted upon said base and horizontally adjustable thereon, a table mounted upon

said saddle and horizontally adjustable thereon, an intermeshing pinion and rack arranged to adjust said saddle, an intermeshing pinion and rack arranged to adjust said table, both of said pinions being mounted within said saddle, and movable therewith in a fixed relative position, a shaft affixed to each of said pinions for the purpose of revolving same, and provided with bearings in said saddle, each of said shafts

extending diagonally outward from said saddle, and means for revolving said shafts, for the purpose specified.

In testimony whereof I affix my signature in presence of two witnesses.

LESLIE H. COLBURN.
